PREFABRICATED BUILDING

Samuel L. De Lisa, 3318 W. Marquette Road,
Chicago, Ill.

Filed July 21, 1961, Ser. No. 66,018

Term of patent 7 years

(Cl. D13—1)

FIGURE 1 is a perspective view of a prefabricated building, showing my design.

FIGURE 2 is a side elevational view thereof, and FIGURE 3 is a top view thereof.

The side not shown in FIGURE 2 is substantially like the side shown in FIGURE 2.

I claim:

The ornamental design for a prefabricated building, as shown and described.
